PROCESS FOR THE NITRATION OF
HALOBENZENESRobert I. Leib, Kirkwood, Mo., assignor to Monsanto
Chemical Company, St. Louis, Mo., a corporation of
DelawareNo Drawing. Filed Jan 4, 1960, Ser. No. 42
20 Claims. (Cl. 260—646)

This invention relates to an improved process for the preparation of nitrohalobenzenes by the nitration of the corresponding halobenzene, whereby a more favorable isomer distribution is obtained.

The present methods used in the preparation of nitrochlorobenzene, for example yield a mixture of the para and ortho isomers, in which the para/ortho ratio is generally around 1.7 or 63% para to 37% ortho. Because of the current and projected demand for the para isomer, a great oversupply of the ortho isomer will result, if this need for the para isomer is fulfilled by using the current methods of making nitrochlorobenzene.

It has been found that the isomer distribution in the nitrohalobenzene product is influenced when the nitration of a halobenzene compound is carried out in the presence of a sulfonic acid. The presence of even small amounts of a sulfonic acid markedly influences the isomer distribution in a nitrohalobenzene product and this effect is still obtained when a high concentration of sulfonic acid is employed, i.e. where 3 moles of sulfonic acid per mole of halobenzene are used. Moreover, the amount of the desired isomer obtained when the nitration is carried out in the presence of a sulfonic acid is greater than the amount obtained in the absence of a sulfonic acid regardless of the nitrating agent or nitrating temperature employed.

The halobenzenes which can be employed in the process of this invention include monochlorobenzene as well as the other monohalogenated benzenes, e.g. monobromobenzene, monoiodobenzene and monofluorobenzene.

Any nitrating agent which is capable of effecting the nitration of an aromatic ring can be used in the process of this invention, e.g. mixed acid, concentrated nitric acid, nitric anhydride, nitrogen tetroxide, ethyl nitrate, etc. Generally, the nitrating agent is employed in stoichiometric quantities, or slightly in excess of the amount required to effect the mononitration of the monohalobenzene. Concentrated nitric acid, which contains 90% or more by weight of HNO_3 is a preferred nitrating agent.

By the term "a sulfonic acid" as used herein throughout the specification and claims is meant any organic sulfonic acid which contains one or more sulfonic acid groups, e.g. organic monosulfonic acids, organic disulfonic acids, organic trisulfonic acids or other organic polysulfonic acids or mixtures thereof, which are at least partially soluble in water. The organic residue of the sulfonic acid can be an aliphatic group such as an alkyl group, a cycloaliphatic group such as a cycloalkyl group, an aromatic group such as an aryl group, or a heterocyclic group.

As illustrative of the aliphatic sulfonic acids there may be mentioned methanesulfonic acid, ethanesulfonic acid, propanesulfonic acid, propanedisulfonic acid, butanesulfonic acid, hexanesulfonic acid, 2-ethylhexanesulfonic acid, dodecanesulfonic acid, tridecanesulfonic acid, pentadecanesulfonic acid, octadecanesulfonic acid, etc., as well as the mixture of sulfonic acids obtained by the sulfonation of kerosene or a mixture obtained by the sulfonation of a high boiling mixture of hydrocarbons from the Fischer-Tropsch process. Illustrative examples of aromatic sulfonic acids contemplated are benzenesulfonic acid, toluenesulfonic acid, benzenedisulfonic acid, ben-

2

zenetrisulfonic acid, ethylbenzenesulfonic acid, diethylbenzenesulfonic acid, dodecylbenzenesulfonic acid, tetradecylbenzenesulfonic acid, octadecylbenzenesulfonic acid, phenylmethylsulfonic acid, phenylpropylsulfonic acid, alphanaphthalenesulfonic acid, betanaphthalenesulfonic acid, 1,5-naphthalenedisulfonic acid, 1,6-naphthalenedisulfonic acid, naphthalene 1,3,6-trisulfonic acid, naphthalene 1,3,5,7-tetrasulfonic acid, etc. Illustrative examples of cycloaliphatic sulfonic acids contemplated are cyclobutanesulfonic acid, cyclopentanesulfonic acid, cyclohexanesulfonic acid, cycloheptanesulfonic acid, cyclohexanedisulfonic acid, methylcyclohexanesulfonic acid, ethylcyclohexanesulfonic acid, butylcyclohexanesulfonic acid, cycloheptane sulfonic acid. Illustrative examples of heterocyclic sulfonic acids are pyridine-3-sulfonic acid, picoline sulfonic acid, pyrrole sulfonic acid, quinoline-8-sulfonic acid, quinoline-5-sulfonic acid, methylacridinetetrasulfonic acid, imidazole sulfonic acid, 3,5-dimethyloxazole sulfonic acid, 3-sulfonic-5-methylfuroic acid, 1,2,8-trisulfonic acid-dibenzofuran, 2-thienyl sulfonic acid, thiophene-2,4-disulfonic acid, thiophene-2,5-disulfonic acid, carbazole-2,7-disulfonic acid, carbazole-1,3,6,7-tetrasulfonic acid, etc.

The aforementioned sulfonic acids may be further substituted by one or more substituents. Typical but not limiting of such substituents are the halogens, such as chlorine, bromine, iodine and fluorine; nitro; carboxy and other non-reactive substituents. Illustrative examples of such as sulfoacetic acid, chloromethane sulfonic acid, trichloromethane sulfonic acid, 3-chloro-thienyl-5-sulfonic acid, 2,8-dicarboxylic acid-4-sulfonic acid dibenzofuran, etc.

The lower alkane sulfonic acids, i.e. those which contain 1 to 4 carbon atoms such as methane sulfonic acid, ethane sulfonic acid, propane sulfonic acid and butane sulfonic acid, constitute a preferred class of aliphatic sulfonic acids. A preferred class of aromatic sulfonic acids are the sulfonic acid derivatives of aromatic hydrocarbons of the benzene series, i.e. benzene and alkyl substituted benzenes in which the alkyl group contains from 1 to 18 carbon atoms.

In cases where the nitrohalobenzene product crystallizes from the reaction medium it may be advantageous to employ an excess of the halobenzene reactant to act as a solvent, or another solvent may be employed, such as a petroleum ether; a saturated aliphatic hydrocarbon, such as hexane, octane, cyclohexane, etc.; or a liquid chlorinated hydrocarbon such as chloroform, carbon tetrachloride or tetrachloroethane.

Effective concentrations of the sulfonic acid in the process of this invention vary in wide ranges depending upon the result desired, in that extremely low amounts, e.g. 0.05 mole of monosulfonic acid per mole of halobenzene to be nitrated will produce the para directive effect. Moreover, as the number of sulfonic acid groups per molecule of sulfonic acid is increased, the amount required to produce a given result is reduced proportionately. Higher yields and higher para isomer content are achieved when the concentration of sulfonic acid is within the range of from about 0.5 to about 2 moles per mole of halobenzene to be nitrated. It is even more preferred to employ from about 1.0 to about 2.0 moles of sulfonic acid per mole of halobenzene to be nitrated. Amounts greater than three moles of sulfonic acid per mole of halobenzene to be nitrated can be used, however no significant increase in either para isomer content or yield results.

A preferred embodiment of this invention is the process for the preparation of paranitrochlorobenzene which comprises reacting concentrated nitric acid with monochlorobenzene in the presence of a mixture consisting essentially of a major portion of a sulfonic acid and a

minor portion of sulfuric acid, the quantity of sulfonic acid added being within the range of from about 0.5 to about 2 moles per mole of monochlorobenzene added. It is preferred that the mixture contain at least about 1.5 parts by weight of sulfonic acid per part of sulfuric acid. It is even more preferred to use a mixture which contains at least 3.0 parts of sulfonic acid per part by weight of sulfuric acid. Expressed on a percentage basis the concentration of the two compounds should be within the range of from about 60% to 90% of sulfonic acid and correspondingly from 40% to 10% sulfuric acid. Such mixtures are desirably obtained from a process for the sulfonation of benzene employing 25-35% oleum, wherein a mixture containing approximately 72% by weight of benzene sulfonic acid, 22% sulfuric acid, 5% water, and 1% of a mixture of sulfones, benzene and benzenedisulfonic acid is obtained.

Those skilled in the art will recognize that the process of this invention is not limited to specific reaction temperatures, since the process can be carried out at temperatures of from -30 to temperatures of 160° C. or more. A reaction temperature of -30° C. can be maintained, for example, by employing a cooling bath comprising a slurry of solid carbon dioxide in acetone and using chloroform as a reaction diluent. As will be appreciated, the rate of reaction at temperatures of from -30° C. to 0° C. will be somewhat slow. The minimum temperature for the process of this invention is therefore that temperature just above that at which no reaction between the nitrating agent and the halobenzene will take place. The maximum temperature is only of economic importance, for it is dependent on economic factors rather than technical factors. For example, the aromatic sulfonic acids will begin to decompose at temperatures above 160° C. and it is, of course, necessary to supply considerable amounts of heat to achieve and maintain reaction temperatures above 90° C. Temperatures within the range of from about 30° C. to about 90° C. are desirably used, while temperatures within the range of from 50° C. to 60° C. are especially preferred.

After the nitration reaction is complete, the product can be recovered from the reaction by any method well known to those skilled in the art. For example, the reaction mixture is permitted to settle into two phases, i.e.,

an organic phase and an aqueous phase. The organic phase is then separated and the aqueous phase is cooled to precipitate the product and the product is removed by filtration. This method can be varied by employing a solvent extraction technique to remove the residual product from the aqueous phase. Preferably, the reaction mixture is diluted with water before the organic phase is separated from the aqueous phase.

The manner of carrying out the process of this invention and the excellent results achieved therefrom will be further apparent from the following specific examples in which all parts and percentages are by weight unless otherwise specified.

EXAMPLE 1

To a well stirred mixture of 176 parts (1.0 mole) of benzenesulfonic acid monohydrate and 112 parts of chlorobenzene there is slowly added 72 parts (1.0 mole) of 90% nitric acid. The temperature is maintained at 50° C. to 55° C. by cooling and the acid is added over a 25 minute period. After all of the acid is in, the reaction mixture is maintained at 50-55° C. for approximately two hours. The resulting mixture is then diluted with 200 parts of water, permitted to separate into two phases and the bottom oil layer is drawn off. The product oil is washed at 70° C. to 80° C. with two aliquots containing 200 parts of water, two aliquots containing 200 parts by weight of a 5% sodium carbonate solution and finally with two additional aliquots of water. The washed oil is then heated at reduced pressure to remove the residual water and any unreacted chlorobenzene. There is obtained 114 parts of nitrochlorobenzene representing a yield of 72%. The product contains about 71% para isomer and about 29% ortho isomer.

The following table represents additional examples of the present invention, wherein the apparatus, procedure and ingredients of Example 1 are utilized except as specified in the table. Generally, the temperature of the reaction, the reaction time, and the molar ratio of monochlorobenzene to nitric acid are the same as in Example 1, exceptions to this appear in the column headed "Remarks." The quantity of sulfonic acid and the specific sulfonic acid are varied as indicated therein, the percentage of yield being based on the monochlorobenzene reactant.

¹ Technical product containing 94% sulfonic acids (mixture of methanesulfonic, ethane sulfonic and propanesulfonic acids), 1% sulfuric acid and 5% water.

EXAMPLE 21

The procedure of Example 1 is repeated except that 248 parts of a mixture containing 71.1% benzenesulfonic acid, 22.1% sulfuric acid and 4.9% water (the balance being made up by various sulfones, benzene and benzene-disulfonic acid) is substituted for the benzenesulfonic acid monohydrate and 129 parts (1.15 moles) of chlorobenzene is used. This provides approximately 1 mole of benzenesulfonic acid per mole of monochlorobenzene and 3.25 parts by weight of sulfonic acid per part of sulfuric acid. There is obtained 245 parts (99% yield) of nitrochlorobenzene. This product contains 69.1% para isomer and 30.9% ortho isomer.

The following table represents additional examples wherein the apparatus, procedure and ingredients of Example 21 are utilized except as specified. In this table the benzenesulfonic acid mixture is identified as "PBSA." The quantity of PBSA and the quantity of chlorobenzene are varied as indicated therein, the variation in chlorobenzene being indicated by the mole ratio of the benzene-sulfonic acid to chlorobenzene.

Table II

Example	"PBSA" Parts	Moles Benzene-sulfonic acid per mole of chlorobenzene	Percent Yield	Percent Para	Remarks
22	248	1.0	99	69.1	
23	111	0.5	80	68.7

28	225	1.02	95.5	72.5	Reaction temperature, 15° C.-20° C.
29	166	0.37	81.9	74	Reaction temperature, 0° C.; 1 mole excess of chlorobenzene employed.
30	225	1.02	97.7	69.8	Water added to reaction mixture before starting nitration to give 8.2% H ₂ O instead of 4.9%.

EXAMPLE 31

To a well stirred mixture of 176 parts (1 mole) of benzenesulfonic acid monohydrate and 225 parts of chlorobenzene previously heated to 45° C., there is slowly added 97.5 parts (1.06 moles) of liquid nitrogen tetroxide (N₂O₄). The N₂O₄ is added over 1½ hour period. After the addition is complete, the reaction mixture is maintained at a temperature of 45° C.-50° C. for two hours. The reaction mixture is then diluted with 200 parts of water, allowed to settle into two phases and the bottom spent acid layer is drawn off. The oil layer is washed with two 400 part aliquots of water, one 400 part aliquot of 5% sodium carbonate solution and again with two 400 part aliquots of water. The excess chlorobenzene is removed at reduced pressure leaving a product having a crystallizing point of 61.8° C. The product contains 73.8% para-nitrochlorobenzene and 26.2% ortho-nitrochlorobenzene.

EXAMPLE 32

The procedure of Example 1 is repeated except that an equivalent amount of bromobenzene is substituted for the chlorobenzene of said example. The nitrobromobenzene is recovered in good yield and contains approximately 70% para isomer.

While this invention has been described with respect to certain embodiments, it is not so limited and it is to be understood that variations and modifications thereof which are obvious to those skilled in the art may be made without departing from the spirit or scope of this invention.

What is claimed is:

1. In a process for the nitration of halobenzene, the improvement which comprises carrying out the reaction in

the presence of a sulfonic acid in an amount which is sufficient to produce a para directive effect.

2. In a process for the production of nitrohalobenzene by the nitric acid nitration of the corresponding halobenzene compound, the improvement which comprises carrying out the nitration in the presence of a sulfonic acid in an amount which is sufficient to produce a para directive effect.

3. A process of claim 2 wherein the halobenzene is monochlorobenzene.

4. A process of claim 3 wherein the sulfonic acid is an aromatic sulfonic acid.

5. A process of claim 4 wherein the sulfonic acid is a sulfonic acid derivative of an aromatic hydrocarbon of the benzene series.

6. A process of claim 4 wherein the sulfonic acid is an aliphatic sulfonic acid.

7. A process for the production of nitrochlorobenzene which comprises reacting monochlorobenzene with concentrated nitric acid at a temperature within the range of from about 0° C. to about 160° C. in the presence of a

16. A process of claim 14 wherein the mixture contains at least 3 parts by weight of benzenesulfonic acid per part of sulfuric acid.

17. A process of claim 16 wherein the mole ratio of sulfonic acid to monochlorobenzene is about 2.0.

18. A process for the production of nitrochlorobenzene which comprises adding a stoichiometric quantity of concentrated nitric acid to a reaction zone containing monochlorobenzene and a mixture consisting essentially of a major portion of an aliphatic sulfonic acid and a minor portion of sulfuric acid, the quantity of sulfonic acid being within the range of from about 1 to about 2 moles per mole of monochlorobenzene and maintaining the temperature within the range of 50° C. to 60° C. throughout the nitration.

19. A process of claim 18 wherein the aliphatic sulfonic acid is a lower alkanesulfonic acid.

20. A process for the production of nitrochlorobenzene which comprises adding a stoichiometric quantity of

8
concentrated nitric acid to a reaction zone containing monochlorobenzene and a chlorobenzenesulfonic acid, the quantity of sulfonic acid added being within the range of from about 1 to about 2 moles per mole of monochlorobenzene and maintaining the temperature within the range of from about 30° C. to 90° C. throughout the nitration.
